COATING APPARATUS

Gordon K. Burns and Samuel Pitt, Westfield, and Daniel V. Waters, Flemington, N. J., assignors to Western Electric Company, Incorporated, New York, N. Y., a corporation of New York

Application April 7, 1943, Serial No. 482,080

1 Claim. (Cl. 91—45)

This invention relates to coating apparatus, and more particularly to apparatus for coating quartz crystal plates with conductive materials.

Quartz crystal plates when used in filters in the communication arts, are coated with aluminum, silver or other suitable conductive materials, and it is important that this coating be of a given thickness uniform throughout.

An object of the invention is to provide an apparatus which is simple in structure, yet highly efficient and practical in coating quartz crystal plates.

With this and other objects in view, the invention comprises a unit actuatable to spray a coating material in a given path and a support for an article having a normal position in a plane substantially parallel with the said path and movable through the path at substantially right angles with respect thereto to be coated with the material.

Other objects and advantages will be apparent from the following detailed description when considered in conjunction with the accompanying drawings, wherein

Fig. 1 is a front elevational view of the apparatus;

Fig. 2 is a side elevational view of the apparatus, a portion thereof being broken away;

Fig. 3 is an enlarged fragmentary sectional view illustrating the power means for moving the article and its support through a coating cycle;

Fig. 4 is a fragmentary sectional view taken along the line 4—4 of Fig. 3;

Fig. 5 is a fragmentary sectional view taken along the line 5—5 of Fig. 3;

Fig. 6 is a fragmentary sectional view taken along the line 6—6 of Fig. 3;

Fig. 7 is a fragmentary sectional view taken along the line 7—7 of Fig. 3, and

Fig. 8 is an enlarged fragmentary top plan view of the article support.

Referring now to the drawings, attention is first directed to Figs. 1 and 2, which illustrate a housing, indicated generally at 10, closed on all sides excepting a portion of its front, indicated at 11, a loading position 12 and an exit outlet 14. A supporting bar 15 has its ends fixed to the housing, as at 16, and extends across the front of the housing substantially midway of the open portion 11. A unit, indicated at 17, is mounted upon the bar adjacent the center thereof. The unit 17 in the present embodiment is a spray gun actuatable, through a handle 18, to force a coating material 19 through a nozzle 20 from a supply tank 21 by air under pressure supplied

by any suitable means (not shown). The material 19 is directed from the unit 17 in a general path which is substantially horizontal and is toward a baffle plate 23 suspended, through the aid of arms 24, from the ceiling of the housing 10.

In the present embodiment articles 25, in the form of quartz crystal plates, are to be moved through the path of the coating material 19, to be coated therewith. A support in the form of an arm 27, having a looped end 28 upon which an arcuate plate 29 is disposed, is fixedly mounted upon an element 30 and is adapted through suitable power means to be moved, from the normal position shown in dotted lines in Fig. 2 and full lines in Fig. 1, through a complete cycle including a substantially vertical position shown in dot and dash lines in Fig. 2.

Referring again to the arcuate plate 29, it will be observed that individual plates 32 are mounted thereon, the latter having projecting pins 33 spaced so as to retain their respective articles 25 (Fig. 8) during the cycle of movement of the arm. The smaller plates 32 may, if desired, be removably supported by the main plate 29 so that other arrangements of retaining pins 33 for different sizes of articles may be mounted thereon for coating of their articles.

Attention is now directed to Figs. 2 and 3 illustrating the power means and other associated mechanism employed in moving the support 27 together with the articles through the coating cycle. This means consists mainly of a unit, indicated generally at 35, mounted upon a frame 36 at an angle of approximately forty-five degrees (45°) from the base of the housing. The power means for this unit includes an electric motor 37 and a reduction gear unit 38, the output end of the latter being indicated at 39 and operatively connected to a one-revolution clutch 40. The inner structure of the clutch 40 may be of a conventional type (not shown), the outer structure thereof including a stop or disengaging portion 41 (Fig. 4) adapted to be engaged by a control lever 42. The control lever 42 (Figs. 3 and 4) is mounted upon a shaft 43 which is journaled in suitable bearings 44 carried by the frame 36. An actuating lever 45 is fixed to the outer end of the shaft 43 and has its outer end pivotally connected, as at 46, to a push rod 47, the latter extending through a supporting bearing 48 mounted in the housing 10 and, through the housing, as shown in Fig. 2, where a push button or handle 50 is mounted upon the outer end thereof. A spring 51 normally urges the rod 47 out-

wardly and serves as means to actuate the lever 45, shaft 43 and control lever 42, to move the latter into engagement with the stop portion 41 of the clutch. The forward movement of the push rod 47, through the control of the spring 51, is limited by a collar 52 mounted upon the push rod and positioned to engage the bearing 48.

A shaft 55, rotatably supported by suitable bearings 56, has one end operatively connected to the clutch 40 and through this connection the shaft is rotated one or more cycles depending upon the operative engagement of the clutch through the actuation of the control lever 42. A brake control cam 57 is mounted upon the shaft 55 between the bearings 56 and has a low portion 58 in the periphery thereof, the latter being cylindrical throughout excepting the low portion. A cam roller 59 is rotatably supported by one end of a bellcrank lever 60 and positioned to ride upon the surface of the cam 57. The lever 60 is mounted upon one end of a shaft 61, the latter being journaled in suitable bearings 62 and having a brake arm 63 mounted upon the opposite ends thereof. The brake arm 63 (Fig. 7) is provided with a suitable brake shoe 64 positioned to engage a brake drum 65.

Returning now to the lever 60 (Fig. 6), it will be noted that an arm 66 thereof is connected to one end of a spring 67, the other end thereof being connected to an adjustable screw 68, the purpose of the spring being to apply force to the brake arm 63 through the lever 60 and the shaft 61 to create a braking force on the shaft 55 through the engagement of the brake shoe 64 with the brake drum 65.

Means is provided, through the control of the rod 47, to render the brake means ineffective if it should be desirable to continue operation of the apparatus through more than one cycle. This means includes a rod 70 (Figs. 3 and 6) slideable longitudinally in a bearing 71 and including a spring pressed plunger 72 in one end thereof adapted to pass beneath the arm 66 of the lever 60 during a time interval when the roller 59 is riding upon the high portion of the cam 57, to lock the lever 60 against movement into the brake applying position when the low portion 58 of the cam reaches the roller. The other end of the rod 70 is connected, as at 73, to the control lever 42, and is moved through this connection during actuation of the rod 47.

Attention is now directed to the outer end of the shaft 55, upon which is mounted a head or collar 75. It will be noted that the brake drum 65 has a reduced portion 76 extending to the head 75, the entire brake drum structure having a sleeve bearing 77 rotatably supporting it upon the shaft 55. The element 30 is mounted upon the reduced portion 76 and is connected thereto in any one of a plurality of positions by a spring pressed plunger or ball member 78 receivable in a plurality of recesses 79. A further connection between the element 30 and the reduced portion 76 includes a pin 80 receivable in an elongate recess 81, the former being carried by the reduced portion 76 while the latter is disposed in the element 30. An annular member 82 is mounted upon the reduced portion 76 concentric with the head 75 and spaced therefrom. In this member, as shown in Fig. 5, are disposed pins 84, 85 and 86. One end of a spring 87 is fixed to the pin 84, the opposite end thereof being connected to a projection 88 which in the present instance is a pin extending through the head 75 and the shaft 55, serving also to positively connect these two mem-

bers together. The pin or projection 88 is positioned between the pins 85 and 86, the latter serving to limit the movement of the shaft and head relative to the portion 76 and to provide positive connection therewith through the projection. A suitable cover 89 is provided for the structures at this end of the shaft 55, this cover being fixedly mounted upon the element 30. At this time attention is directed to portion 90 of the element 30, which provides additional weight at the side opposite the arm 27 to serve as a counterbalancing portion.

Upon considering now the operation of the apparatus, let it be assumed that the supporting arm 27 is in the position shown in Figs. 1 and 2, that is, the dotted line position shown in Fig. 2. After placing the articles 25 between the sets of pins 33 upon the plates 32, the operator may push the rod 47 inwardly through the aid of the button 50, to move the lever 42 free of the portion 41 of the clutch, allowing the clutch to engage, connecting the shaft 55 with the power means 37 and 38, resulting in rotation of the shaft in the direction of the arrow (Fig. 3). For a single cycle of operation, the operator need only move the rod 47 sufficiently to release the clutch and may at that time release the rod 47, allowing the force of the spring 51 to cause the free end of the lever 42 to ride upon the adjacent wall of the clutch until the portion 41 is again presented thereto after the complete cycle of operation. At that time the force of the spring 51 will move the lever 42 into position in engagement with the portion 41, resulting in disengagement of the clutch and stopping of the apparatus. The stopping of the apparatus is assisted by the brake applying means. As soon as the cycle of operation begins, the roller 59 (Fig. 6) rides out of its low portion of the cam 57, freeing the brake shoe 64 from the drum 65, and for the major portion of the operating cycle rides upon the high portion of the cam. However, as the cam approaches the end of its cycle, the low portion thereof is presented to the roller and the force of the spring 67, through the lever 60, causes the brake shoe 64 to apply a braking force upon the drum 65, tending to stop rotation of the shaft 55.

Attention is now directed to the articles 25 on the supporting arm 27. At a suitable time after the releasing of the clutch to start the cycle of operation, the operator may press the lever or handle 18 to actuate the spray unit 17, causing the material 19 to be sprayed in the given path which is substantially parallel with the normal position of the articles. However, during the cycle of operation of the apparatus, the angular mounting of the operating means with respect to the housing 10 and also the supporting arm 27 results in the movement of the supporting arm together with the articles through a plane which, when traversing the path of the material, is at right angles with respect thereto. Thus the articles are substantially in vertical positions, where they may be uniformly sprayed or coated with the material. The excess material will pass on to the baffle plate 23 aided by suitable exit means associated with the exit outlet 14. Through the power means, namely the clutch associated with the motor and speed reducing unit assisted by the brake, the arm together with the articles will be returned to the normal position, where they will come to rest. At this time the coated articles may be removed and other articles to be coated may be disposed in place.

It is important that the supporting arm together with the articles be relieved of any jerking movements during the operating cycle thereof. This is of particular importance at the beginning and the end of the operating cycle, where the support and articles are put into motion from a stationary position and brought again to the stationary position from a movement of a given speed during the operating cycle. The cushioning means interposed between the shaft or power means and the arm includes the spring 81. At the beginning of the cycle of operation the pin or projection 88 (Fig. 5) is held in engagement with the pin 85 through the force of the spring 87. At the beginning of the cycle of operation 10 the spring 87 is the only connection between the shaft 55 and the arm 27 through the reduced portion 76 and the element 30. Therefore, upon releasing of the clutch for connection of the shaft 55 with the power means, any jerking movement of the structure connected to the shaft is absorbed by the spring 87, which will assist in starting movement of the arm, the positive connection between the shaft and the arm taking place when the projection 88 engages the pin 86. Furthermore, when the clutch is disengaged at the end of the operating cycle, stopping rotation of the projection 88, the arm may continue at a slower rate of speed through the force of the spring 87 until the pin 85 again engages the projection 88.

It should be understood that if desired the operation of the apparatus may be continued through a plurality of cycles by holding of the rod 47 inwardly, to hold the clutch released during the selected interval or until the last chosen cycle has begun. At the same time the plunger 72 (Figs. 3 and 6) will hold the lever 60 outwardly, as shown in Fig. 6, to hold the brake shoe 64 away from the brake drum 65. However, upon 40

releasing the rod 47 the clutch will be disengaged through the lever 42 and the portion 41 and the brake shoe 64 will be allowed to apply its braking force, assisted by the spring 67, to the brake drum 65. Furthermore, through the aid of the spring pressed plunger 78, the arm 27, through the element 30, may be adjusted to any one of a plurality of positions on the reduced portion 76.

Although specific improvements of the invention have been shown and described, it will be understood that they are but illustrative and that various modifications may be made therein without departing from the scope and spirit of this invention as defined by the appended claim.

What is claimed is:

A coating apparatus comprising a unit operable to spray a coating material in a substantially horizontal path, a shaft mounted for rotation about its axis which extends at an angle of approximately 45° from a true horizontal plane, an arm extending diagonally relative to the axis of the shaft and from one end of the shaft where the adjacent inner end of the arm is fixedly mounted on the shaft, a support for a substantially flat article secured to the outer end of the arm to support the article in a plane parallel with the arm, and means to rotate the shaft one revolution, from a loading position where the arm with the support and the article will lie in substantially horizontal planes, to move the arm through a conical path to move the support with the article through the path of the coating material at substantially right angles with respect to the said path of the coating material to cause coating of the article with the material and to return the arm with the support and coated article to the loading position.
